UNITED STATES PATENT OFFICE.

HUGO RICHARD PAUSIN, OF ALLENDALE, NEW JERSEY.

CLOSURE.

1,426,211.

Specification of Letters Patent. Patented Aug. 15, 1922.

Application filed March 23, 1921. Serial No. 454,883.

To all whom it may concern:

Be it known that I, HUGO R. PAUSIN, a citizen of the United States, and resident of the town of Allendale, in the county of Bergen and State of New Jersey, have invented a new and Improved Closure, of which the following is a full, clear, and exact description:

My invention relates to a closure, and more particularly a receptacle closure.

It is a well appreciated fact that it has been necessary to provide various receptacles for the housing of certain substances, and articles, which receptacles would provide a closure which might readily be operated to effect an opening of the same.

These closures have, for the most part, presented defects, in that the same were susceptible to damage in the rough usage to which receptacles are subjected while being shipped. Further the closure was liable to come open, incident to the receptacle being dropped or thrown in handling, so as to expose, and in many instances spoil the contents of the same.

With this in view, I have provided a closure which is ideally adapted for use in connection with receptacles of the class stated, and more particularly receptacles adapted to contain motion picture films, and by means of which, primarily, the elements effecting a retention of the closure are guarded against injury.

A further object of my invention is the provision of a device of the character specified, in which means will be provided serving to prevent any accidental opening of the closure irrespective of the rough usage to which it may be subjected.

Further objects of my invention will appear in the annexed specification, taken in connection with the drawings which latter present one practical embodiment of my invention, and in which;

Figure 1 is a partly fragmentary plan view of a receptacle closure, and elements for retaining the same in applied position.

Figure 2 is a sectional side view taken along the lines 2—2 in the direction of the arrows indicated in Figure 1.

Figure 3 is a sectional view taken along the line 3—3 and in the direction of the arrows also indicated in Figure 1.

Figure 4 is a similar section taken along the line 4—4 and in the direction of the ar-

rows also indicated in the figure specified, and

Figures 5 and 6 are perspective views of detached portions of the closure securing means embodying my improved construction. 60

Referring now more particularly to Figures 1 and 2 it will be seen that the reference numeral 10 indicates the body of a receptacle, which in the embodiment illustrated, is of a construction permitting of the shipping of motion picture films, and which has a lid forming a closure 11, associated with it.

It will be noted, however, that contrary to the conventional construction, that the lid 11 forming the closure, is provided with a 70 sunken or recessed part 12 in its upper face, and mounted in this recessed part, are the elements providing the fastening means for the closure, it being also noted, assuming that the thickness of these elements does not 75 exceed more than substantially the depth of the recessed portion, that these elements will be protected from receiving any blows delivered against the lid 11, aside from the fact that the recessed portion of the lid will 80 also strengthen this member.

Referring now more particularly to the elements providing the fastening which serves to retain the lid in its proper position it will be noted that I utilize a latch member, 85 which includes the body portion 13 formed with a longitudinally extending opening 14, and the edge of the body portion adjacent the outer end of the opening 14 is outstruck so as to form a stop 15. Also the rear end of 90 the body portion 13 may be conveniently bent so as to form a finger portion 16 by means of which the latch may be manually retracted.

The latch is slidably associated with the 95 upper face of the lid within the recessed portion by means of a guide plate 17 formed with a raised portion 18 serving to accommodate the body of the latch, and it will be noted that by positioning the outer edge of 100 the guide plate 17 adjacent the wall formed by the recessed portion 12, that the stop 15 of the latch will co-act with this wall, and prevent a projection of the latch beyond a predetermined point. It is also to be noted 105 that a spring 19 is associated with the guide plates 17, and latch proper, and that a certain portion of the body of this spring rests within the opening 14, its ends contacting respectively with the rear end of the raised 110

portion 18 and the stop 15, thus serving to normally effect a projection of the latch, and to retain the same in the position illustrated in Figures 1 and 2, it being noted 5 that a seal may be applied through the opening 16' of the finger portion 16, and through the opening 17' of the plate 17 to prevent an unauthorized opening of the receptacle without this being detected.

10 Any conventional means may be provided for hingedly or otherwise securing the lid 11 in its proper position, and to also provide a co-operating element for the lid 13, I preferably utilize a pair of outwardly extending 15 ears 20 forming a part of the lid 11, which ears project beyond the plane into which the edge of the same extends, and pass through openings forming a part of the body of the receptacle 10. Thus, when the 20 lid is in seated position, and the latch has the outer end of its body portion projecting through an opening also formed in the side walls of the body 10 of the receptacle, it will be noted that any movement on the part of 25 the lid 11 is precluded. Further, upon the latch being retracted, it will be obvious that the ears 20 co-operating with the openings formed to accommodate the same will act in a certain capacity as a detachable hinge permitting 30 ready access to be had to the interior of the receptacle.

To now provide means which will serve as an element permitting of the carrying of the entire unit, and which will also lock the 35 latch against any movement I utilize a handle 21 which is rockingly mounted upon the lid 11 by means of a plate 22, it being noted that a spring 23 is employed, which co-operates with the handle 21 and plate 22, to 40 cause the former to normally occupy the position indicated in full lines in Figures 1 and 2.

In this position it will be noted that the body of the handle lies adjacent to the finger portion 16 of the latch, and thus any 45 retraction of the latter is prevented.

It will thus be noted that I have provided a closure for a receptacle, which closure has associated with it a fastening means, and is 50 constructed in such a manner, that a maximum of protection will be provided for the fastening means. It will also be noted that although the handle serves as an element by means of which the entire unit may readily 55 be carried, that should the unit be dropped or occupy a position of rest, that the handle will immediately swing from the position indicated in dotted lines in Figure 2 to that indicated in full lines, it being obvious 60 that in the latter position any retraction of the latch sufficient to permit of a disengagement of the lid 11 from the body of the receptacle 10 is prevented.

Obviously numerous modifications of 65 structure might readily be resorted to with-

out in the least departing from the spirit of my invention, which I claim as:

1. A closure for a receptacle, including a lid adapted to be applied to a receptacle, a latch secured to said lid and being adapted 70 to co-operate with said receptacle to retain the same in applied position, and a handle for carrying said receptacle, said handle being movably secured to said lid and being adapted to co-operate with said latch to normally prevent a retraction of the same. 75

2. The combination with a receptacle, of a lid adapted to be associated with the same, a guide plate secured to said lid, a latch slidably associated with said guide plate, a 80 spring co-operating with said latch and adapted to normally project the same, a handle for carrying said receptacle, said handle being hingedly secured to said lid, and means for normally swinging said 85 handle to a position adjacent the rear end of said latch to prevent a retraction of the same.

3. The combination with a receptacle, of a lid adapted to be associated with the same, a 90 guide plate secured to said lid, a latch slidably associated with said guide plate, a spring co-operating with said latch and adapted to normally project the same, a handle hingedly secured to said lid, and a 95 spring co-operating with said handle and adapted to swing said handle to a position at which it will lie adjacent the rear end of said latch to prevent a retraction of the same. 100

4. A closure including in combination with a receptacle, of a lid adapted to be associated with said receptacle, a guide plate secured to said lid, a latch movably associated with said guide plate, said latch including a body 105 portion formed with a longitudinally extending opening, a stop adjacent the outer end of said opening, and a spring adapted to partially lie within said opening and co-operating with said stop to project said latch. 110

5. A closure including in combination with a receptacle, of a lid adapted to be associated with said receptacle, a guide plate secured to said lid, a latch movably associated with said guide plate, said latch including a body portion formed with a longitudinally extending opening, a stop adjacent the outer end of said opening, and a spring adapted to partially lie within said opening and co-operating with said stop to project 115 said latch, said body portion terminating in a finger portion. 120

6. A closure including in combination with a receptacle, of a lid adapted to be associated with said receptacle, a guide plate secured to 125 said lid, a latch movably associated with said guide plate, said latch including a body portion formed with a longitudinally extending opening, a stop adjacent the outer end of said opening, and a spring adapted to par- 130

tially lie within said opening and co-operating with said stop to project said latch, said body portion terminating in a finger portion, a handle hingedly secured to said lid, and a spring adapted to normally swing said handle to a point adjacent the outer face of said finger portion.

5 7. A closure for a receptacle including a lid adapted to be applied to a receptacle, a latch secured to said lid and being adapted to co-operate with said receptacle to retain the same in applied position, and a handle

independent of said latch and adapted to normally co-operate with the same to prevent a retraction of said latch.

15

8. A closure for a receptacle including a lid, a normally projected latch carried by said lid and adapted to retain the same in closed position with respect to the body of said receptacle, a handle for carrying said receptacle, said handle normally bearing against said latch to prevent a retraction of the same.
